REFLECTIVE GOLF PUTTER HEAD

Frank C. Loggins, 4365 S. Eagle Circle,
Denver, Colo. 80232

Filed Jan. 14, 1974, Ser. No. 432,907

Term of patent 14 years

Int. Cl. D21—02
U.S. Cl. D34—5 GH

FIG. 4FIG. 5FIG. 6FIG. 7

FIG. 1 is a perspective view of a reflective golf putter head showing my new design;

FIG. 2 is a right side view thereof;

FIG. 3 is a left side view thereof;

FIG. 4 is a top view thereof;

FIG. 5 is a front view thereof;

FIG. 6 is a bottom view thereof; and

FIG. 7 is a rear view thereof.

The broken lines indicating the lower portion of a golf club shaft are for illustrative purposes only.

I claim:

The ornamental design for a reflective golf putter head, as shown and described.
